SLEEPING CAR

Robert A. Shields, Bloomsburg, Pa., assignor to
American Car and Foundry Company, New
York, N. Y., a corporation of New Jersey

Application July 25, 1946, Serial No. 686,242

12 Claims. (Cl. 105—315)

1

This invention relates to sleeping cars in general and in particular to single room sleeping cars in which the rooms are adapted for dual occupancy when necessary.

In recent years the trend in sleeping car construction has been toward the room type of accommodation. To date the most economical form of room accommodations are those having a bed foldable longitudinally of the car and having a width of approximately thirty-three inches. Due to the narrowness of this bed it is impossible for two persons to sleep therein with any degree of comfort. However, in order to economize and cut down travel expenses a considerable number of people are willing to put up with the discomfort for a short period. Two average sized people can readily sleep with a fair degree of comfort in what is commonly known as a three-quarter size bed, that is, a bed having a width of approximately forty-five inches. It is an object, therefore, of the present invention to so arrange the bed in a room type of car as to give three-quarter size beds on opposite sides of the aisle, which beds extend longitudinally of the car for maximum passenger comfort.

A further object of the invention is the provision of a railway car having room accommodations with substantially three-quarter size beds therein and so arranged that the rooms may be connected in pairs thus allowing a family of four to travel in comfort and absolute privacy yet at a minimum of expense.

A yet further object of the invention is the provision of a railway car having room type accommodations on either side of the aisle with the rooms arranged in pairs and access gained thereto through a single aisle door.

A still further object of the invention is the provision of a railway car having rooms arranged in pairs on either side of the aisle and separated by stub partitions and swinging doors which latter hide the toilet facilities when in their fully open position.

Yet another object of the invention is the provision of a railway car having room type accommodations so arranged and equipped with beds as to accommodate a total of forty people in an eighty-five foot car.

These and other objects of the invention will be apparent to persons skilled in the art from a study of the following description and accompanying drawings, in which

Figs. 1 and 2 are sectional views taken through the car and showing the floor plan, with Fig. 1 showing the right half of the car and Fig. 2 the left half;

Fig. 3 is an enlarged view showing the paired room accommodations;

Fig. 4 is a sectional view taken substantially on line 4—4 of Fig. 3;

2

Fig. 5 is a sectional view taken substantially on line 5—5 of Fig. 3;

Fig. 6 is a sectional view taken substantially on line 6—6 of Fig. 3, and

Fig. 7 is a sectional view taken substantially on line 7—7 of Fig. 4.

Referring now to the drawings in detail, it will be seen that the car skeleton is formed on a floor 2, side walls 4 having windows 6 therein and joined together by roof structure 8, which is also joined to the end walls 10 of the car. As shown in Figs. 1 and 2 the right hand end of the car is provided with a vestibule entrance 12, while the left hand end of the car shown in Fig. 2 is provided with spaces 14 for the storage of car supplies and the accommodation of the switch gear and air conditioning equipment. As clearly shown in Figs. 1 and 2 the bulk of the rooms is shown as intended for ordinary day use although the one room A has been shown with its entrance door moved to the position normally used only at times when the occupant would be retiring. In Fig. 2 rooms B are shown as made up for night use, while room C is shown as made up by the passenger so that he may recline alongside the window during the daytime.

As clearly shown in Figs. 1 and 2 the rooms are arranged in pairs on either side of the central aisle D. The room pairs are bounded by the car side walls and by the aisle walls 20 which are joined to the car side walls by transverse partitions 22. Intermediate the transverse partitions 22 are stub partitions 24 joined to the car side wall at one edge and carrying at the other inner edge hinged doors 26. As shown most clearly in Fig. 3 these doors 26 may swing from a fully open position parallel to the car side walls to an angular position indicated in full lines in Fig. 3. The vertical abutting edges of the doors or panels 26—28 are provided with any conventional form of fastener for locking these parts together, such locks being operated by means of a handle shown at X in Fig. 5. In this angular position the doors 26 meet hinged flaps 28 pivotally connected to the aisle wall structure adjacent the edges of door opening 30. The flaps 28 will normally be carried in a position substantially at right angles to the aisle wall but can be unlocked and moved to the broken line position of Fig. 3, in which position they can cooperate with the door 26 to give an increased dressing space for the occupants of the room. In case the paired rooms are sold for family occupancy a sliding door 32 may be moved across the doorway, in which case the doors 26 need not be used to secure privacy for the family. With the sliding doors closed, the doors 26 may be placed parallel to the car side walls, that is, in the position shown in room E of Fig. 2.

60 Mounted on either side of the stub partitions

24 are preferably unit assemblies, comprising a toilet bowl or hopper unit T, above which is carried a folding wash basin or lavatory unit L, while above the wash basin is mounted a cabinet M for toilet articles or medicines. As shown the toilet bowl or hopper unit is provided with an upholstered lid 34 thus permitting its use as a seat in the room. It will be seen that by arranging the toilet cabinets as shown they will be completely hidden from aisle view when doors 26 are thrown back as shown in room E Fig. 2.

Each room is provided with movable seats S of the type in which the back and arms at least can fold downwardly so as to be out of the way when the bed is in its down-folded or operative position. Each room is also provided with a couch 36 hinged to the side wall by means of an angle or other structure 38 and adapted to hang vertically alongside the car wall when in an inoperative position and to be supported in a substantially horizontal position extending along the car beneath the window as shown in Fig. 6. In the horizontal or operative position of the couch legs 40 will fold down out of the couch into engagement with the car floor so as to support the couch and its occupants. Mounted on the room side of the transverse partitions 42 are wardrobes W adapted to receive clothing or other passenger articles and these wardrobes, as clearly shown in Figs. 6 and 7, do not extend downwardly to the floor but terminate at a point above the bed when in its inoperative position. Baggage racks 42 are also provided in each room and these racks are mounted on the stub partitions 24 which, of course, extend from car side wall to aisle wall above the openings for doors 26 and 32.

The bed 50 will normally be carried in a vertical position alongside the aisle wall 20 as most clearly seen in Fig. 4. The bed is provided on its ends adjacent one side edge with pins 52 adapted to slide vertically in slots formed in guide structures 54 carried on partitions 22 and narrow end members 56 fastened to the aisle wall adjacent the edges of door opening 30. One of the ends adjacent the opposite side of the bed is also provided with a pin 58 adapted to slide in a curved slot formed in a guide member 60 fastened on the transverse partition 22. The weight of the bed is mainly counterbalanced by a spring or other resilient member 62 anchored at one end to the aisle wall 20 adjacent the ceiling 64 and connected at its other end to a block 66. The block 66 has connected thereto two cables 68, one of which connects directly to a pin 52, the other of which fastens around pulleys 70 for connection with the other pin 52. Locks, of course, are provided on narrow partitions 56 so as to hold the bed against accidental displacement. Upon release of the locks the bed may be pushed laterally toward the car side wall with the spring or other resilient member 62 lifting the lower side of the bed until it has assumed its horizontal position as shown by broken lines in Figs. 4 and 5. The same locks which held the bed in its inoperative position may be used to lock the inner or aisle side of the bed in its horizontal or operative position. The outer or window side of the bed will not require any locks since its own weight will retain it against movement due to its engagement with angle structure 38 on which the couch 36 is mounted. When it is desired to lower the bed it is, of course, first necessary to fold the chair S, after which the bed may be moved to its horizontal position by a person standing at the end of the bed and where necessary in the space ob-

tained by moving the door 26 and flap 28 to the broken line position of Fig. 3 or to the full line position of room A Fig. 1.

By arranging the room and mounting the bed as described a bed of full length and approximately forty-five inches width can be made available in each room while still leaving sufficient space for bed operation in absolute privacy. Provision of such a bed extending substantially the entire distance from side wall to aisle wall of a standard railway car will permit occupancy of the room by two persons. In case the room has two occupants it may be desirable to add another loose seat S, although the second occupant may wish to use the folding couch 36 extending alongside the window and preferably provided with an inclinable portion such as is used in hospital and other beds.

While the railroad car has been described more or less in detail with specific reference to the accompanying drawings, it will be obvious to persons skilled in the art that various modifications and rearrangements of parts may be made and all such modifications and rearrangements of parts are contemplated as will fall within the scope of the appended claims defining my invention.

What is claimed is:

1. A railway car having a central aisle and a space on either side of the aisle and each space being defined by transverse walls joining an aisle wall and a side wall, a pair of beds in each said space and disposed in end to end relationship along said aisle wall, an aisle door opening in said aisle wall disposed between the adjacent ends of the beds and giving access to said space, said aisle door opening and beds together occupying substantially all of the aisle wall joining the transverse walls of each space, an aisle door slidably carried by said aisle wall and slidably to cover said door opening, a stub transverse partition extending from the side wall toward said aisle door, a pair of doors hinged to the inner edge of said partition and each extending when closed from the partition substantially to the inner edge of the adjacent bed to divide said space into a pair of rooms each having a bed which when in use occupies substantially the entire floor area of the room.

2. A railway car having a central aisle and a space on at least one side thereof defined by transverse walls joining an aisle wall and a side wall, a pair of beds in said space disposed in end to end relationship along said aisle wall, an aisle door opening in said aisle wall and occupying substantially the entire aisle wall between the adjacent ends of the beds, an aisle door slidably carried by said aisle wall and slidably to cover said door opening and to give access to said space, a stub transverse partition extending from the side wall toward said aisle door, a pair of doors hinged to the inner edge of said partition and each extending when closed from the partition substantially to the inner edge of the adjacent bed to divide said space into a pair of rooms each having a longitudinally disposed bed therein, said pair of doors and aisle door defining a common entry way for each room adjacent an end of the bed.

3. A railway car having a central aisle and a space on at least one side thereof defined by transverse walls joining an aisle wall and a side wall, an aisle door closing a doorway disposed in said aisle wall intermediate said transverse walls, narrow partitions extending into said space

either side of the aisle doorway, a pair of beds in said space and each disposed longitudinally along an aisle wall and occupying substantially the entire aisle wall between a narrow partition and the adjacent transverse wall, a stub transverse wall connected to said side wall and extending transversely of the car intermediate the planes of said narrow partitions, doors hinged to said stub transverse wall and cooperating with said narrow partitions to divide said space into a pair of rooms each having a longitudinally disposed bed therein.

4. A railway car having a central aisle and a space on at least one side thereof defined by transverse walls joining an aisle wall and a side wall, an aisle door closing a doorway disposed in said aisle wall intermediate said transverse walls, narrow partitions extending into said space either side of the aisle doorway, a pair of beds in said space and each extending longitudinally of the aisle wall from a narrow partition to the adjacent transverse wall, a stub transverse wall connected to said side wall and extending transversely of the car intermediate the planes of said narrow partitions, doors hinged to said stub transverse wall and cooperating with said narrow partitions to divide said space into a pair of rooms, said narrow partitions each including a flap hinged thereto and swingable away from the adjacent bed and having its free edge cooperable with the free edge of its associated door to provide increased dressing space at the end of the bed.

5. A railway car having a central aisle defined by spaced aisle walls, a transverse wall joining a side wall and an aisle wall to define three sides of a room at one side of the aisle, a bed extending laterally along the aisle wall and when in inoperative position being vertically disposed alongside said aisle wall and movable to an operative horizontal position substantially spanning the space between the aisle wall and side wall, and a door at least partially defining the fourth wall of said room and giving access thereto at the end of the bed, said bed when in operative position also substantially spanning the space between said door and transverse wall.

6. A railway car having a central aisle defined by spaced aisle walls, a transverse wall joining a side wall and an aisle wall to define three sides of a room at one side of the aisle, a bed extending laterally along the aisle wall and when in inoperative position being vertically disposed alongside said aisle wall and movable to an operative horizontal position substantially spanning the space between the aisle wall and side wall, and a door at least partially defining the fourth wall of said room and giving access thereto at the end of the bed, said bed when in operative position also substantially spanning the space between said door and transverse wall, said door when closed being angularly disposed relative to said bed to give dressing space within said room at the end of the bed when in operative position.

7. A railway car having a central aisle defined by spaced aisle walls, a transverse wall joining a side wall and an aisle wall to define three sides of a room at one side of the aisle, a bed extending laterally along the aisle wall and when in inoperative position being vertically disposed on its side alongside said aisle wall and movable to an operative horizontal position substantially spanning the space between the aisle wall and side wall, a stub transverse wall connected to the side wall and extending toward the aisle wall

in a plane spaced from a plane through the adjacent end of the bed, a toilet unit disposed in said room and attached to said stub transverse wall, a door hinged to said stub wall and when closed extending at an angle thereto to provide a dressing space in the room bounded partly by said bed, toilet unit and door and said bed when in operative horizontal position overlapping part of said toilet unit and extending substantially from said door to said transverse wall.

8. A railway car having a central aisle defined by spaced aisle walls, a transverse wall joining a side wall and an aisle wall to define three sides of a room at one side of the aisle, a bed when in inoperative position being vertically disposed on its side alongside said aisle wall and movable to an operative horizontal position substantially spanning the entire space between the transverse wall, aisle wall and side wall, a stub transverse wall connected to the side wall and extending toward the aisle wall in a plane adjacent to but spaced from a plane through the adjacent end of the bed, a toilet unit disposed in said room and attached to said stub transverse wall, a door hinged to said stub wall and when closed extending at an angle thereto to provide a dressing space in the room bounded partly by said bed, toilet unit and door, and a couch pivoted to said side wall and swingable from a vertical to a horizontal position when said bed is in its inoperative position and together with said toilet unit extending from the transverse wall to the stub transverse wall.

9. A railway car having a central aisle and a space to one side thereof defined by transverse walls joining an aisle wall and a side wall, an aisle opening disposed in said aisle wall intermediate the planes of said transverse walls, a stub transverse wall extending from said side wall toward the center of said aisle opening and terminating in spaced relation thereto, toilet units disposed on either side of said stub transverse wall, and doors hinged to said stub wall at the inner end thereof adjacent the toilet units and oppositely swingable to open position paralleling said side and aisle walls and when open hiding said toilet units from view through said aisle opening.

10. A railway car having a central aisle and a space to one side thereof defined by transverse walls joining an aisle wall and a side wall, an aisle opening disposed in said aisle wall intermediate the planes of said transverse walls, a fixed stub transverse wall extending from said side wall toward the center of said aisle opening but terminating short thereof and at least partially dividing said space into a pair of adjoining rooms, a pair of doors hinged to the inner edge of said stub wall and oppositely swingable to an in line open position paralleling said aisle wall and when closed defining with said walls said pair of rooms, and an aisle door closing said aisle opening whereby said rooms may be joined by a straight sided passageway defined by said aisle door and pair of doors when the latter are in open position.

11. A railway car having a central aisle and a space to one side thereof defined by transverse walls joining an aisle wall and a side wall, an aisle opening disposed in said aisle wall intermediate the planes of said transverse walls, a stub transverse wall extending from said side wall toward the center of said aisle opening but terminating short thereof, toilet units disposed on either side of said stub transverse wall, doors

hinged to said stub wall adjacent the inner vertical edge thereof and oppositely swingable to open position paralleling and intermediate said aisle and side walls and when in such open position hiding said toilet units from view through said aisle opening, and an aisle door slidably carried by said aisle wall for closing said aisle opening and defining with said first named doors when closed a triangular shaped entry space for access to either room.

12. A railway car having a central aisle defined by spaced side walls, a transverse wall joining a side wall of the car and an aisle wall to define three sides of a room at one side of the aisle, a bed extending longitudinally of the car and inoperative position being disposed vertically on its side edge alongside aisle wall and being movable to an operative horizontal position substantially spanning the entire space between the transverse wall, aisle wall and side wall, said bed being accessible for occupancy from the end opposite said transverse wall, means for supporting said bed along its longitudinal edges when in its horizontal operative position, and a closure

5
